1,954,283

BEDSTEAD

Guy C. Cross, Watervliet, Mich.

Application June 16, 1933, Serial No. 676,031

8 Claims. (Cl. 5—318)

The main objects of this invention are to provide a bedstead having a foot portion adapted to be adjusted to constitute a holder for bedding or the like so that it is readily accessible and at the same time the weight thereof is not on the feet of the occupant and at the same time a structure which is attractive in appearance.

A further object is to provide a structure accomplishing these ends which may be economically embodied in bedsteads of standardized types.

Objects relating to details and economies of my invention will appear from the description to follow. The invention is defined and pointed out in the claims.

A structure which is a preferred embodiment of my invention is illustrated in the accompanying drawings, in which:

Fig. 1 is a perspective view of a bedstead embodying my invention adjusted to provide a holder or support for bedding or the like, the roll of bedding being indicated by dotted lines.

Fig. 2 is a fragmentary longitudinal section, the foot panel being shown by full lines adjusted as a holder and in upright position by dotted lines.

Fig. 3 is a horizontal section on line 3—3 of Fig. 4.

Fig. 4 is a vertical section on line 4—4 of Fig. 2. Fig. 5 is a fragmentary plan view partially in section to show structural details.

Fig. 6 is a fragmentary vertical section corresponding to that of Fig. 2 of a slightly modified mounting of the foot panel.

In the embodiment of my invention illustrated, 1 represents the head frame and 2 the foot frame, these parts being connected by the longitudinal rails 3.

The structure illustrated is provided with a bottom 4 on which the spring or mattress is disposed. The foot frame, in the embodiment illustrated, is provided with a foot board 5 having a horizontal slot 6 therein. On the outer side of the foot frame I mount a foot panel 7 which when swung to erected position constitutes a finish part and foot board extension for the foot frame. This foot panel is preferably hinged at 8. It is yieldingly held in its upright or erected position by means of the blade spring 9, the inner end of which is disposed on the inside of and secured to the foot board by means of screws 10. This spring has a longitudinal slot 11 at its outer end engaging the pin 12 providing a pin and slot connection for the spring to the

panel. This spring acts to yieldingly hold the panel in erected position.

The panel may be swung to an outwardly inclined position relative to the foot board, as shown in Fig. 2. The strut 13 pivoted to the foot board at 14 acts to hold the panel in this outwardly inclined position against the tension of the spring, the strut collapsing against the outer side of the foot board so as not to constitute a material obstruction to the foot panel 7. A finger recess 15 is formed in the foot board to permit engagement of the strut.

A flexible support, preferably in the form of a plurality of straps 16, is secured at one end to the inner side of the panel 7 by means of the bar 17 overlapping the ends of the strap, the other ends of the straps being secured upon the upper edge of the foot board by means of the beading or finishing strip 18.

With this arrangement, the panel is swung to its outwardly inclined or collapsed position as the straps coact therewith to form a holder for articles such as a roll of bedding, for example, as indicated by dotted lines at 19, Figs. 1 and 6. With this arrangement of parts, the bedding may be folded or rolled up and arranged on this support so that it is conveniently accessible and also so that it does not obstruct the lower portion of the bed and the weight thereof is not on the feet of the occupant which occurs when persons six feet in height occupy a bed of the average length.

In the modification illustrated by Fig. 6, the panel 20 is hinged at its lower outer edge to the upper outer edge of the foot frame 21 at 22, the foot board 23 being positioned at the inner side of the foot frame and extending thereabove, as illustrated. Otherwise the arrangement of parts and operation of the device is substantially similar to that shown in Figs. 1 to 5, inclusive. The mattress is indicated in dotted lines at 24.

I have illustrated and described my improvements in an embodiment which I consider highly practical. I have not attempted to illustrate or describe certain embodiments and adaptations which I contemplate as it is believed that this disclosure will enable those skilled in the art to which my invention relates to embody or adapt the same as may be desired.

Having thus described my invention, what I claim as new and desire to secure by Letters Patent, is:

1. The combination in a bedstead of a foot frame including a footboard having a horizontal slot therein, a foot panel hinged at its lower

edge upon the outer side of said foot frame and constituting when in erected position a finish part thereof, a blade spring secured at one end on the inner side of said footboard to project 5 through said slot therein and having a pin and slot connection for its other end to said panel, an arm hinged to said footboard to collapse against the same, the panel collapsing over said arm when the panel is in erected position, said 10 arm being adapted to be swung to erected position to hold said panel in an outwardly inclined relation relative to said footboard, and a flexible support secured to said panel and to the upper edge of said footboard and coacting with the 15 panel when it is in collapsed position to constitute a holder for bedding and the like.

2. The combination in a bedstead of a foot frame including a footboard, a foot panel hinged at its lower edge upon the outer side of said foot 20 frame and constituting when in erected position a finish part thereof, and a flexible support secured to said panel along a horizontal line spaced below the top of the panel and to the upper edge 25 of said footboard, said support itself being adapted to constitute a holder for bedding and the like when the panel is swung outwardly from the frame.

3. The combination in a bedstead of a foot frame, a foot panel hinged at its lower edge upon 30 the outer side of said foot frame and constituting when erected an extension and finish part therefor, a spring for yieldingly holding said panel in erected position, means for holding said panel in an outwardly inclined position relative to 35 said foot frame, and a flexible support connected to said foot frame and to said panel to collapse between the foot frame and panel when the panel is erected and to constitute an article holder when the panel is in collapsed position.

4. The combination in a bedstead of a foot 40 frame, a foot panel hinged at its lower edge upon the outer side of said foot frame and constituting when erected an extension and finish part therefor, and a flexible support connected to said 45 foot frame and to said panel to collapse between the foot frame and panel when the panel is erected and to constitute an article holder when the panel is in collapsed position.

50

55

60

70

75

5. The combination in a bedstead, of a foot frame, a panel hinged to said foot frame to swing outwardly therefrom, a spring on the inner side of said panel acting to hold it in erected position, a collapsible strut on the inner side of said panel adapted to hold it in its collapsed position against the tension of said spring, and a flexible support secured at one end to said panel and at the other end to said frame to collapse between the same when the panel is in erected position and to constitute an article holder when the panel is in collapsed position. 80

6. The combination in a bedstead, of a foot frame, a panel mounted on said foot frame to swing outwardly therefrom, and a flexible support secured at one end to said panel along a horizontal line spaced below the top of the panel and at the other end to said frame to collapse between the same when the panel is in erected position, said support itself being adapted to constitute an article holder when the panel is in collapsed position. 85 90

7. The combination in a bedstead, of a foot frame including a footboard, a foot panel hinged at its lower edge upon the outer side of said footboard to swing outwardly therefrom, a spring for yieldingly holding said panel in erected position, means for holding said panel in collapsed position against the tension of said spring, and a plurality of flexible straps secured at one end 100 to said panel and at the other to the upper edge of said footboard and coacting with the panel when it is in collapsed position to constitute a holder for bedding and the like. 105

8. The combination in a bedstead, of a foot frame, a foot panel mounted on said frame to swing outwardly therefrom, a flexible support secured to said frame and to said panel, said support itself being adapted to constitute a holder for bedding and the like when the panel is swung 110 outwardly from the frame, and means for holding said panel in outwardly inclined position relative to said foot frame so that said flexible support hangs down at the middle along a horizontal line between the frame and panel to form 115 a cradle. 120
